(57) **CLAIM**

The ornamental design for a fishing camera positioner as shown and described.

DESCRIPTION

FIG. 1 is a perspective view of a fishing camera positioner showing my new design;

FIG. 2 is another perspective view thereof;

FIG. 3 is a front side elevational view thereof;

FIG. 4 is a rear side elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures depict portions of the fishing camera positioner that form not part of the claimed design.
